UNITED STATES PATENT OFFICE.

CHARLOTTE NUEBLING, OF NEW YORK, N. Y.

DESIGN FOR A HAT ORNAMENT.

SPECIFICATION forming part of Design No. 36,978, dated June 14, 1904.

Application filed May 19, 1904. Serial No. 208,787. Term of patent 3½ years.

To all whom it may concern:

Be it known that I, CHARLOTTE NUEBLING, a citizen of the United States, residing at New York, borough of Manhattan, in the county of New York and State of New York, have invented a new, original, and ornamental Design for a Hat Ornament, of which the following is a specification.

Reference being had to the accompanying drawing, forming a part hereof, the figure illustrates a perspective view showing my new design for a hat ornament.

I claim—

The ornamental design for a hat ornament substantially as herein shown.

CHARLOTTE NUEBLING.

Witnesses:

C. A. WEED,
JOHN O. SEIFERT.
